UNITED STATES PATENT OFFICE.

JOHN ARTHUR LEES, OF KIDDERMINSTER, COUNTY OF WORCESTER, ENGLAND, ASSIGNOR TO HORNER BROTHERS, OF PHILADELPHIA, PA.

DESIGN FOR A CARPET.

SPECIFICATION forming part of Design No. 13,116, dated August 1, 1882.

Application filed June 21, 1882. Term of patent 3½ years.

To all whom it may concern:

Be it known that I, JOHN ARTHUR LEES, of Kidderminster, Worcestershire, England, have invented and produced a new and original Design for Carpets, of which the following is a specification.

The nature of my design is fully represented in the accompanying photographic illustration, to which reference is made.

I claim as my invention—
The design for a carpet, as shown.

JOHN ARTHUR LEES.

Witnesses:

JAMES A. MORTON,
Solicitor, Kidderminster.
